(57) **CLAIM**

The ornamental design for a rice dispenser, as shown and described.

DESCRIPTION

FIG. 1 is a top, front and right side perspective view of a rice dispenser showing my new design;

FIG. 2 is a front elevation view thereof;

FIG. 3 is a rear elevation view thereof;

FIG. 4 is a left side elevation view thereof, the right side elevation view being a mirror image thereof;

FIG. 5 is a top plan view thereof;

FIG. 6 is a bottom plan view thereof; and,

FIG. 7 is a bottom, front and left side perspective view thereof.

In the drawings, the broken lines in FIGS. 6 and 7 depict portions of the design that form no part of the claim.
